UNITED STATES PATENT OFFICE

FRANK MOSSBERG, OF ATTLEBORO, MASSACHUSETTS, ASSIGNOR TO MOSSBERG PRESSED STEEL CORPORATION, OF ATTLEBORO, MASSACHUSETTS, A CORPORATION OF MASSACHUSETTS

REEL

Application filed July 26, 1928. Serial No. 295,415.

This invention relates to reels; and has for its object to so form the heads of the reel that the barrel may be readily centered with relation to the head and firmly secured there-
5 to.

A further object of the invention is the provision of a circular outwardly-extending rib on the head of the reel to assist in stacking the reels end on end.

10 A still further object of the invention is the deflecting of the sheet stock of the head to form a recess on the inside to center and assist in securing the barrel to the head and to form a rib on the outer surface for the purpose of assisting in stacking the reels end on end.

15 The invention further consists in the forming of a pocket at the juncture of the barrel and head for the reception of welding material which may be cut away to avoid a fillet at the juncture to provide a greater space to be occupied by wire wound upon the reel.

20 With these and other objects in view, the invention consists of certain novel features 25 of construction, as will be more fully described, and particularly pointed out in the appended claims.

In the accompanying drawings:

25 Figure 1 is a top plan view showing the head of the reel.

Figure 2 is a sectional view of the head and the barrel shown just before being assembled.

30 Figure 3 is a sectional side view through the reel with the heads and barrel in assembled relation.

Figure 4 is an enlarged detail sectional view showing the welding material in position, the section being taken on line 4—4 of
40 Figure 1.

Figure 5 is a sectional detail taken through one of the ribs on line 5—5 of Figure 1.

45 Figure 6 is a side elevation showing several of the reels stacked end to end slightly out of alignment but yet firmly supported by means of the formations on the head.

Figure 7 is a sectional view of a modified construction of reel showing the head held on by bolts.

50 In the construction of reels it is found de-

sirable to provide a means for positively centering the barrel with reference to the head and also to provide an outer surface for sliding the reels one across the other in stacking; and in order to accomplish both of these results in a single construction, I have deflected the stock of the head to form a circular recess on the inner side of the head with a corresponding circular rib on its outer surface which serves to assist in sliding the reels one over the other in stacking them and at the same time I have so formed one of the walls of the circular recess as to leave a pocket for the reception of welding material which after being positioned may be cut away to leave a square corner for the reception of wire or other material to be reeled; and the following is a detailed description of the present embodiment of this invention and showing the preferred means by which these advantageous results may be accomplished:

With reference to the drawings, 10 designates the head formed of sheet stock with its peripheral edge 11 rolled outwardly to provide a rim 12 and also the head stock is deflected outwardly about its center to form a hub 13, the outer surfaces of the hub 13 and the rim 12 being in substantially the same plane, as shown.

55 The sheet stock of the head 10 is pressed outwardly to form a circular rib 14 on the outer surface of the head with a corresponding depression or recess 15 on the inner surface of the head for receiving the end 16 of the tubular barrel 17. The outer surface of the rib 14 is located in the same plane as the outer surface of the hub 13 or the rim 12 so as to afford a supporting surface for sliding one reel on the other in end on end stacking.

60 The inner wall 18 of the recess 15 extends at substantially right angles to the general plane of the head 10 and parallel to the axis of the reel and serves to center the barrel 10 with relation to the head, while the outer or distal wall 19 of the recess 15 is inclined away from the surface of the barrel to leave a pocket 20 for the reception of welding material 21 for positively and permanently welding the barrel and head of the reel together.

65 70 75 80 85 90 95 100 In applying the welding material, it builds

up similar to that illustrated at 22, in dotted lines, in Figure 4, at the juncture between the head and the barrel, which material is machined away to form a square corner, as illustrated in full lines, in Figure 4, and in Figure 5 to allow additional space for the wire or other material to be reeled, without weakening the joint at the juncture of these two parts.

10 Radial ribs 23 are provided extending outwardly from the circular rib 14 to assist in stiffening and strengthening the heads, while a tubular sleeve 24 may extend through the barrel to assist in tying the heads thereto, 15 which sleeve 24 is welded or suitably secured to the hubs 13 of the heads.

In the modification shown in Figure 7, the recess 25 is pressed out to just fit the ends of the barrel and the tie rods 26 hold the heads 20 on the barrel.

It will be apparent from the foregoing that, by pressing out the circular formation in the head, I have stiffened the same, provided a suitable surface for sliding one reel 25 on another, formed a means of centering for the barrel and head and provided a pocket for a welding joint by which the head and barrel may be welded together without the welding material occupying space which may 30 be used for reeling.

The foregoing description is directed solely towards the construction illustrated, but I desire it to be understood that I reserve the privilege of resorting to all the mechanical 35 changes to which the device is susceptible, the invention being defined and limited only by the terms of the appended claims.

I claim:-

1. A reel comprising a tubular barrel, a 40 head on each end thereof having a continuous circular recess therein for receiving one end of the barrel, one wall of the recess forming a pocket with the end of the barrel and welding material in said pocket to secure the 45 barrel to the head.

2. A reel comprising a tubular barrel, a head on each end thereof having a continuous circular recess therein for receiving one 50 end of the barrel, the wall of the recess nearest the axis of the barrel being substantially perpendicular to the general plane of the head to center the barrel and the distal wall of the recess being inclined to leave a pocket between it and the barrel, and welding material positioned in said pocket to secure the 55 barrel to the head.

3. A reel comprising a tubular barrel, a head on each end thereof having a continuous circular recess therein for receiving one 60 end of the barrel, the wall of the recess nearest the axis of the barrel being substantially perpendicular to the general plane of the head to center the barrel and the distal wall of the recess being inclined to leave a pocket 65 between it and the barrel, and welding ma-

terial positioned in said pocket to secure the barrel to the head, said welding material having a surface substantially in the plane of the inner surface of said head and at right angles to the outer surface of the barrel.

4. A reel comprising a pair of sheet metal heads with outwardly extending stiffening peripheral rims, each head having the sheet stock deflected to form a continuous circular recess on the inside and a continuous circular projection on the outer surface thereof extending outwardly substantially the distance of said rims, one wall of each recess forming a pocket with the end of the barrel adjacent thereto, a tubular barrel extending between said heads with its ends secured in said recesses, and welding material positioned in said pockets to secure the barrel to the heads.

5. A reel comprising a tubular barrel, a sheet metal head at the end thereof having its stock deflected to form a continuous circular rib on the outer side and a continuous circular recess on the inside receiving the ends of the barrel, the wall of the recess nearest the axis of the barrel being substantially perpendicular to the general plane of the head to center the barrel and the distal wall of the recess being inclined to leave a pocket between it and the barrel, and welding material positioned in said pocket to secure the barrel to the head.

6. A reel comprising a pair of sheet metal heads with outwardly extending stiffening peripheral rims, each head having its sheet stock deflected to form a continuous circular recess on the inside and a continuous circular projection on the outer surface thereof extending outwardly substantially the distance of said rims, a tubular barrel extending between said heads one wall of each recess forming a pocket with the end of the barrel adjacent thereto, welding material positioned in said pockets to secure the barrel to the heads, and radial strengthening ribs extending outwardly from the surface of said heads in substantially the same plane with and intersecting said circular rib.

In testimony whereof I affix my signature.
FRANK MOSSBERG.
